X-RAY EQUIPMENT

Lionel E. Weyenberg, Milwaukee, Wis., assignor
to X-Ray Shoe Fitter, Inc., Milwaukee, Wis., a
corporation of Wisconsin

Application August 2, 1940, Serial No. 349,691

10 Claims. (CL. 250—53)

This invention relates to improvements in X-ray equipment.

It is the primary object of the invention to provide novel, improved and simplified means for the mechanical and electrical disposition of X-ray equipment in a cabinet such, for example, as the cabinet of a machine used for the fitting of shoes by X-ray. I propose to eliminate the expense incident to the separate disposition of each individual part in the cabinet by providing an assembly of the X-ray tube, the transformer and the tube supports which can be unitarily inserted in the cabinet in conjunction with a co-operating housing for the tube in which the tube is readily accessible and which nevertheless provides protection for the operator and the user.

The objects will be more apparent from study of the following disclosure of the invention.

In the drawings:

Fig. 1 is a view in vertical section of a foot X-ray machine embodying the invention.

Fig. 2 is a fragmentary detail view partially in front elevation and partially in section on an enlarged scale, showing the housing and the X-ray tube therein.

Fig. 3 is a detail view partially in plan and partially in horizontal section, showing the organization of the X-ray tube and its housing, its mount, and its transformer casing.

Fig. 4 is a detail view taken in section on the line 4—4 of Fig. 3.

Like parts are identified by the same reference characters throughout the several views.

The cabinet comprises a base section 5 having a platform at 6 and a viewing chamber at 7, the viewing chamber having a recessed bottom portion 8 in the plane of the platform 6 and constituting an extension thereof into which the wearer's foot may be introduced for inspection. Above the recessed portion of the viewing chamber is a fluorescent screen 9 and the top of the chamber provides eye pieces 10 and 11 by means of which the image fluorescent on the screen 9 may be viewed.

At the rear the cabinet provides a control chamber 15 within which is mounted the thermostatic time controlling relay set 16 as described in my companion application of even date which is entitled Thermostatically controlled timing relay circuits. On the inclined top wall 17 of the control chamber are mounted switches 18 and instruments, etc. A single conduit 19 leads downwardly from the junction box 20 to the entire X-ray image which forms the

particular subject matter of the present application.

In accordance with the present invention the X-ray tube is supported from the transformer case and a separate housing encloses the mounted tube. The transformer case 22 contains a suitable transformer at 23 and supports a rheostat 24 which may be set in accordance with the line voltage to supply the correct current to the transformer. On the top of the transformer case 22 is a junction box 25 in which the electrical connections are made between the controls, the transformer, and the rheostat.

The front wall of transformer case 22 comprises a panel 26 in which are fixed to project forwardly a pair of laterally spaced dielectric tubes 27 and 28 having corresponding notches at 29 and 30 near their outer ends. These notches are just sufficiently large to receive the ends of the X-ray tube 31, leaving the filament terminals 32 and 33 and the high tension terminal 34 exposed beyond the supporting tubes 27 and 28. The leads to the filament terminals are carried from the transformer 25 through the tubular mounting supports 27 and 28 and are brought out through suitable openings in the side walls of the mounting supports as shown in Fig. 3. The filament leads include a connection to a rheostat 35.

From the foregoing it will be apparent that the X-ray tube, its supporting mounts, and the electrical connections thereto, are all unitarily assembled with the transformer and the transformer case, thus permitting unitary handling and complete pre-wiring so far as this portion of the apparatus is concerned.

Immediately ahead of the transformer case in the lower section 5 of the cabinet is the metal tube housing 37 which protects the tube and confines its discharge. A large opening at 38 in the rear wall of the housing 37 receives the mounting supports 27 and 28 for the X-ray tube and, if desired, may be large enough to receive the tube itself, mounted on such supports. Because the housing 37 and the transformer case 22 are mutually complementary and are placed in abutment, there is no accurate fitting necessary and the opening 38 may be as large as desired to permit the convenient manipulation of the parts into their desired relationship.

An opening at 39 in the top wall of housing 37 directs and confines the discharge from the X-ray tube. There is a door opening at 40 in the front wall closed by a hinged door 41 which, when closed, seats against a switch 42 connected

in series with the conductors which supply current to the transformer 25, the arrangement being such that said switch 42 is biased to open itself whenever door 41 is opened, thereby cutting off current and de-energizing the transformer and tube as a safety measure.

It will be apparent that by reason of the organization of the tube housing 37 and the transformer case and tube mounts, the assembly of the X-ray equipment in the cabinet for the purposes described, is greatly simplified.

I claim:

1. X-ray equipment comprising the combination with a transformer, of tubular bracket means projecting laterally from the transformer, each of the tubular bracket means having a transverse notch in its upper peripheral portion, an X-ray tube resting in the notches of the tubular bracket means, and electrical connections extending in part through the tubular bracket means between the tube and the transformer.

2. X-ray equipment comprising the combination with a cabinet provided with a viewing chamber and a fluorescent screen, of a housing below the viewing chamber having an aperture for directing rays toward said screen, an X-ray tube in the housing, an adjacent transformer case positioned laterally of the housing and provided with bracket means projecting into the housing, said housing being apertured to receive the bracket means and said case abutting the housing to close the aperture therein, a transformer in said case, and electrical connections from the transformer to the tube, said tube being mounted on said bracket means.

3. A device of the character described comprising the combination with an X-ray transformer and tube, of a case for the transformer, tube mounts carried by the transformer case and upon which said tube is mounted externally of the transformer case, said transformer case, tube and tube mounts being adapted to be handled as a unit, and a ray confining housing for the tube having a back aperture normally closed by said transformer case, said case and housing having generally parallel wall portions in one of which said housing back aperture is located and through which aperture the tube mounts and tube are movable with the tube carried in said mounts, said case and housing being freely separable without disturbing the aforesaid unit, and said tube and mounts being wholly exposed upon the removal of said housing from its position contiguous to said case.

4. X-ray equipment comprising the combination with a cabinet provided with a supporting platform and a viewing chamber above the platform and having an X-ray compartment below the platform, of a ray confining housing immediately below the platform having an opening directed upwardly toward the under surface of the platform and having another opening at its rear through which a mounted X-ray tube is freely receivable, and a transformer and transformer case in unitary assembly and provided unitarily with a pair of spaced arms projecting forwardly and adapted to receive an X-ray tube and at least partially to enclose the wiring therefor, whereby the transformer, transformer case, mounting, arms and tube constitute a unit completely wired for operation, said housing opening being adapted to receive the arms and tube of said unit and being freely disengageable from said case for the complete exposure of said arms and unit, the length of said arms being such as

to position the tube centrally in said housing beneath said platform when said case is disposed behind said housing at the rear of said platform.

5. A device of the character described comprising the combination with a cabinet provided in its bottom with an X-ray compartment and having above said compartment a platform and a viewing chamber, said cabinet having a door in front of said platform affording access to said compartment, of a transformer case at the rear of said compartment having a transformer therein and provided with supporting arms projecting forwardly toward said door to a position centrally beneath said platform, an X-ray tube mounted in said arms and constituting a unit with said case and transformer, and a housing adapted to confine the rays from said tube and having a rear opening abutting said case and closed thereby through which said opening, said tube and arms are freely receivable, whereby said housing is freely applicable to and removable from said case, the removal of said housing being adapted completely to expose said tube and arms, and said housing having a forward door accessible through the door of said compartment for affording limited access to said tube.

6. The device of claim 5 in which the said housing is provided with a door actuated transformer switch having door actuated means for the closing of said switch only when said door is closed.

7. X-ray equipment, comprising the combination with a cabinet provided with a viewing chamber and a fluorescent screen, of a housing generally L-shaped in cross section disposed below and laterally of the viewing chamber provided with an aperture for directing light rays toward said screen, a door at the front of the housing, an enclosed transformer mounted within said housing and provided with tube supporting brackets extending toward the housing door, an X-ray tube mounted on the brackets, and an X-ray shield enclosing the tube and detachably engaging the transformer, said shield opening toward the screen and having a wall hinged to open toward the housing door to permit installation and removal of the tube therethrough.

8. The device as set forth in claim 7, wherein said cabinet includes a control chamber above the rear portion of said L-shaped housing and adjacent the viewing chamber.

9. X-ray equipment comprising the combination with a transformer and a transformer case, of a pair of tubular arms mounted on the transformer case and projecting forwardly therefrom, said arms being provided at points spaced from their free ends with upwardly opening notches, an X-ray tube having a central bulbous portion and reduced terminal portions mounted on said arms with said reduced terminal portions positioned within the notches of said tubular arms, wiring extending from the transformer and along the arms and operatively connected with said X-ray tube, said transformer, transformer case, arms, tube and wiring being adapted to be handled as a unit from which, however, said X-ray tube is freely detachable by disengaging the wiring and lifting the tube from the notches of the arms, and a housing having a back abutting the transformer case and an opening in said back normally closed by said case but of sufficient size to pass the X-ray tube and said arms and the associated wiring without disturbing said unit, said housing comprising shielding for said tube and having an opening for X-rays vertically

above said tube and being provided in its front wall with a door opposite said rear wall opening through which said tube is accessible without separating said housing and said case.

10. An X-ray shoe fitting device including a cabinet comprising a base having a platform and a control chamber, a viewing chamber extending over said platform and upwardly beside said control chamber and provided with a fluorescent screen spaced above the platform, a transformer and transformer case permanently mounted in the base beneath the control chamber, mounting arms projecting from said transformer case beneath the platform, an X-ray tube mounted on said arms and wired unitarily to the transformer, 15

a shielding housing having an X-ray opening upwardly directed to deliver rays from said tube through said platform, said housing having a rear wall generally paralleling the side of said transformer case and provided with an opening normally closed by said case and of sufficient size to pass said arms and tube, said housing having a door through which said tube is accessible, and said cabinet being provided with a door through 10 which the housing door and said tube are accessible and through which said housing may be withdrawn from said case leaving the unitarily assembled tube and wiring fully exposed within the cabinet.

LIONEL E. WEYENBERG.
